UNITED STATES PATENT OFFICE.

LEONARD LANCASTER MERRIFIELD, OF TORONTO, CANADA, ASSIGNOR TO
EDWIN JAMES CHECKLEY, TRUSTEE, AND ECONOMICAL GAS APPARATUS
CONSTRUCTION COMPANY, LIMITED, OF TORONTO, CANADA.

GAS-PRODUCER.

SPECIFICATION forming part of Letters Patent No. 707,146, dated August 19, 1902.

Application filed June 24, 1901. Serial No. 65,825. (No model.)

To all whom it may concern:

Be it known that I, LEONARD LANCASTER MERRIFIELD, mechanical engineer, of the city of Toronto, in the county of York, in the Province of Ontario, Canada, have invented certain new and useful Improvements in Gas-Producers, of which the following is a specification.

My invention relates to improvements in gas-producers for producing gas from peat, sawdust, and other organic substances; and the object of the invention is to provide a machine of this class particularly adaptable for the production of gas from peat, in which the carbonic-acid gas, which is non-combustible, may be reduced into carbon monoxide, which is a combustible gas, and thereby materially increase the amount of burning power in the resultant gas; and it consists, essentially, of a shell lined with fire-brick and provided with two chambers having grates with central perforated upwardly-extending portions, feeding-retorts preferably conical in form and surrounded by gas-flues, which form a means of communication between the chambers through the medium of a connecting passage-way, gas-outlets at the bottom of each chamber above the grates, suitable conduits being provided at the back of the casing for cooling the gas as it passes from the retort and at the same time heating the air as it passes to a point beneath the grates, as hereinafter more particularly explained.

Figure 1 is a perspective view, partially from the rear, showing the general form of my gas-machine, portion of the casing being broken away to exhibit portion of the mechanism. Fig. 2 is a vertical section looking from the front. Fig. 3 is a detail of the mechanism for controlling the valves. Fig. 4 is a detail of the upper shaft and arms controlling the valves. Fig. 5 is a detail of the lower shaft and arms. Fig. 6 is a detail perspective view taken from the rear of Fig. 3. In the drawings like characters of reference indicate corresponding parts in each figure.

A is the shell of the machine, and B a central partition.

C is the lining, of fire-brick, which is so

formed as to form two chambers D D' of equal area, at the bottom which are located the grates E E. Each of the chambers D D' has located above it a retort F, which is in the form of a frustum of a cone. It will be noticed that the lower portions of the chambers D are tapered, as shown. It will be noticed also that the ash-pit G has a substantially conical bottom G', provided with a suitable valve g, the chute g' of which extends into a water seal g². The shell is supported on suitable hollow standards A'. The grates E are revolving grates and are provided with the central perforated dome e, covered with fire clay or bricks e', also provided with perforations. The blast passing through these perforations serves to keep the bed of peat at the bottom of the grate incandescent, as will hereinafter appear.

Surrounding the chambers D D' at the bottom are a series of passage-ways e², extending radially outwardly into an annular chamber e³. These passage-ways are designed to convey the gas from the bottom of the chamber to the conduit leading to the main, as will hereinafter appear. At the inwardly-extending or tapered upper portion of the chambers D, I provide a series of openings or passage-ways d, which extend vertically upwardly into annular chambers D², which are connected together at the top by a cross passage-way D³, into which extends the gas-outlet flue I. The outlet-flue I is provided with a suitable valve i, which is manipulated through the valve-stem i' and handle i².

J represents suitable charging-hoppers at the top, which are made in any suitable manner, such as may be found most convenient and suitable.

It will be noticed on reference to Fig. 1 that the outlet-flue I is connected at the top by the branch I' with the conduit J', which is located and supported in the main rectangular chamber K. It will also be noticed that I provide a passage-way e⁴ at the back of each chamber D D', which communicates with the outlet-pipes e⁵, which in turn communicate with the conduit J', being provided, however, at the top or end with a cap e⁶, which

may be opened or closed, as the occasion may require, the cap shown in the drawings, however, being open.

The conduit J' connects, by means of a pipe 5 j' , with a conduit J^2 , at the bottom of which is an opening J^3 , to which is connected a pipe for conducting gas to any desired point.

L is an opening leading into a fresh-air conduit L' , which extends around the conduit J^2 10 and central partition L^2 , around the conduit J' , and down to the bottom thereof, whence it passes through by the pipe l into the bottom of the ash-pit immediately below the grate. The outer end of each conduit l is provided 15 with a cap l'' , as indicated in Figs. 1, 3, and 6.

It will now be seen that there are practically two pipes for the admission of the fresh air into the bottom of the retorts and two pipes for the outlet of gas from the bottom 20 portions of the retorts, and the first two pipes are provided with caps l'' and the latter with caps e^6 . (See Fig. 3.) The caps l'' are provided with stems l^2 , which have pivotally connected to them the cross-beam l^3 , which is secured 25 on the cross-shaft 2. The cross-shaft 2 is supported in suitable bearings 2^a , as indicated, and has secured onto it an arm 3.

4 is a counter cross-shaft situated above the shaft 2 and having located thereon the 30 sleeve 5. The shaft 4 is journaled in suitable bearings. The sleeve 5 has secured on it the arms $6\ 6'$, and the shaft 4, journaled in bearings 4^a , has secured on it the arms $7\ 7'$. The end of the arm $6'$ is pivotally connected 35 to the stem e^7 at the upper end of the cap e^6 , and the end of the arm $7'$ is pivotally connected to the end of the stem e^7 of the duplicate cap e^6 . The end of the arm 6 has pivotally attached to it the connecting-rod 8, and 40 the end of the arm 7 has pivotally connected to it the connecting-rod 9. The connecting- rods 8 and 9 are made in two parts, the socket portions $8'$ and $9'$ being pivotally connected to the ends of the cross-beam l^3 . The socket 45 portions $8'$ and $9'$ have bosses 8^2 and 9^2 , which are provided with slots.

11 and 12 are pins which normally extend through the bosses, socket portions, and stems of the connecting-rods 8 and 9, respectively. The pins 11 and 12 are provided with laterally-extending pins 11' and 12', which extend through slots in the bosses, so as to limit the movement of the pins. The ends of the pins 11 and 12 have connected to them 55 the adjusting-rods 11² and 12², which extend to the outside of the casing. The arm 3 has connected to it an adjusting-rod 3', which also extends through to the outside of the casing.

60 In the position shown in Fig. 3 the connecting-rods 8 and 9 are each shown connected together, and it will therefore be seen that by manipulating the adjusting-rod 3' the cap e^6 is thrown up and down simultaneously 65 with the diagonally-situated cap l'' in both cases, so that when the cap l'' is open for admission of air through the pipe l beneath one

chamber D' the gas-outlet pipe e^5 is open at the bottom of the opposite chamber for a purpose as will hereinafter appear. By pulling upon the adjusting-rods 11² and 12² the upper portions of the connecting-rods 8 and 9 are thrown out of connection with the lower portion—that is to say, the caps e^6 are thrown out of working in unison with the caps l'' . 70 In doing this of course it is preferable first to pull upon the rod 3', so as to throw the cross-beams l^3 and 10 horizontal, and likewise the arms 6 and 7 and 6' and 7'. It will thus be seen that as soon as the two portions of the rods 8 and 9 are disconnected the caps e^6 will drop down, so as to cover the pipes e^5 , and necessarily the rods 8 and 9 will drop farther down into the sockets $8'$ and $9'$. The caps l'' , however, will be raised and the 85 pipes l opened for a direct draft through the pipe l underneath the chambers D and D', the gas in this instance passing up through the opening d , cross passage-way d^3 , into the pipe L , the valve i , of course, of which is 90 open.

I shall now briefly describe the operation of my invention. The chambers D and D' are filled with peat fuel or sawdust or other organic substances up to about a point slightly 95 above the gas-outlets d . Fire is then kindled in both chambers, and the caps l'' are adjusted so as to be raised and open, while the caps e^6 close the pipes e^5 , as hereinbefore described. When the fuel in the chambers D and D' is 100 brought to a proper degree of temperature—viz., that of incandescence—the rods 8 and 9 are connected to their socket portions and are arranged to act in unison. (See Fig. 3.) It will thus be seen that when the cap e^6 is 105 open, so as to uncover the pipe e^5 , the diagonally-situated cap l'' is also open, so as to uncover the pipe l . The forced draft, by any suitable means created, is preferably used and forced through the pipe l into the bottom of one chamber D, the gas from the incandescent peat being thereby forced through the passage-ways d and cross passage-way D^3 and annular passage-ways d^2 through the passage-way d at the opposite side, whence 115 the gas passes down through the second bed of incandescent peat and out through the gas-openings e^3 into the pipe e^5 , thence out through the conduits J' and J^2 to the main gas-supply pipe. In order to keep the bed of peat 120 in each chamber incandescent, it is necessary to frequently change the valves or caps, closing the draft and gas-outlet pipes, which work in unison, and this is accomplished by the means I have hereinbefore described, so as 125 to throw the caps, which are closed in Fig. 3, open and the caps which are open closed. The main draft thus would be directed through the adjacent chamber in identically the same manner and down through the opposite chamber by the passage-ways hereinbefore referred to, thence through the outlet-pipe. Not only may the air be admitted through the pipe L' , but also steam may be admitted 130

through this pipe, and, the air and steam passing through the grate E' and perforated cone into the fuel, where partial combustion takes place, the resultant gases with the excess moisture in the peat passing up through the flues or passage-ways as hereinbefore described. I find in practice it is necessary to change the position of the valves or caps for the pipes e^6 and l frequently to produce the best effects. After a great deal of experiment I have found that I am enabled to practically eliminate the carbonic-acid or non-combustible gas and water vapors or, more properly, to convert them into carbonic oxide and hydrogen, which pass out through the flue into the preheating device hereinbefore described, where the sensible heat of the gas is taken up by the air which surrounds the flues and travels in the opposite direction, the gas passing through the outlet J^3 to washers, scrubbers, condensers, or gas-holders or where required. As soon as the peat is raised to a state of combustion in the chambers D and D' by direct draft, as hereinbefore described, I feed the peat into the conical retorts F and F' . The moisture of the peat will now be eliminated to a great extent for the reason of the radiation of heat from the flues and passage-ways d and D^2 around the conical retorts F and F' . The charging is accomplished with sealed cone-valve hoppers, as hereinbefore referred to, or by suitable screw-feed, as may be preferred. It will thus be seen that in starting the furnace the charges of peat in both retorts are raised up to incandescence. The valves are then so set that the gases from one of the retorts or producers are obliged to pass through the incandescent mass of the companion producer. Fresh peat is then fed into the producer from which the gases pass, and the air-blast is turned on in this producer, and thus the gases produced, which are mainly carbon dioxid and steam, are passed through the incandescent fuel in the companion producer. This converts the carbon dioxid and steam into carbon monoxid and hydrogen. This process is continued until the incandescence in the second producer is reduced to too low a temperature to break up the gases from the first producer. When this point is arrived at, the valves are shifted and the process reversed. The producers are so designed as to insure the complete breaking of all tarry matter and the conversion of all the carbon dioxid and the water vapors into carbon monoxid and hydrogen. The air and steam are introduced at the bottom of one chamber, and the gas is thrown up at the bottom of the other. When the driers are working, a charge of peat and wood sawdust or other carbonaceous material is let down, say, into the left-hand chamber, and the steam and air are blown into the bottom of the said chamber. The products of distillation pass through the incandescent coke and then through the flue and top pipe to the right-hand chamber, down

through the hot coke which it contains, and out through the bottom flues and away to the gas-main. When the fuel is partly carbonized, a charge is let down into the right-hand chamber and the valves are reversed. The direction of the current is reversed every few minutes either automatically or by hand. The reversing of the apparatus is governed by the amount of carbon dioxid in the resultant gases at such period, so that the temperature of the coke in the second chamber is always kept sufficiently high to decompose the tarry matter and the carbon dioxid into carbon monoxid and the water vapor contained in the peat or carbonaceous material into carbon monoxid and hydrogen. The resultant product is therefore carbon monoxid and hydrogen (water-gas) and traces of marsh-gas. The coke is used up in the further converting of the oxygen into carbon monoxid. The clinkers and incombustible matter gradually fall to the base of the fuel, where they are removed by the shaking or revolving grate and fall into the hopper-bottom, which is provided with a valve, as described, where they give up all the sensible heat to the incoming air and steam and from the hopper-bottom drop from time to time through the valve into the water seal and after the valve is closed can be withdrawn without stopping the production of gas. It is of course preferable to produce the best results to hermetically seal the fire-box at the bottom with a valve, so as to prevent the evaporation from the water ascending into the fuel-bed, and thereby surcharging the fuel-bed with moisture.

What I claim as my invention is—

105

1. In a peat-gas machine, the combination with a suitable casing and lining therefor and two peat-burning chambers formed therein adjacent to each other and provided with suitable grates, feeding-retorts located above the peat-burning chambers and designed to contain peat preparatory to burning, a series of passage-ways extending upwardly from the upper portion of each peat-burning chamber circularly arranged and surrounding the retorts, and annular chambers connected therewith, a cross passage-way connecting the annular chambers, a series of passage-ways or flues leading radially outwardly near the bottoms of the peat-burning or fire chambers, annular passage-ways surrounding the bottom of the chambers and connecting with said radially-extending flues and gas-outlets from each annular chamber as and for the purpose specified.

115

2. In a peat-gas machine, the combination with a suitable casing and lining therefor and two peat-burning chambers formed therein adjacent to each other and provided with suitable grates, feeding-retorts located above the peat-burning chambers and designed to contain peat preparatory to burning, a series of passage-ways extending upwardly from the upper portion of each peat-burning chamber

120

125

- circularly arranged and surrounding the retorts and annular chambers connected therewith, a cross passage-way connecting the annular chambers, a series of passage-ways or flues leading radially outwardly near the bottoms of the peat-burning or fire chambers, annular passage-ways surrounding the bottom of the chambers and gas-outlets from each annular chamber and valves for controlling the same and draft flues or pipes leading to beneath the grates and connected with the central gas-flues of each retort and valves controlling the same as and for the purpose specified.
5. In a peat-gas machine, the combination with a suitable casing and lining therefor and two peat-burning chambers formed therein adjacent to each other and provided with suitable grates, feeding-retorts located above the peat-burning chambers and designed to contain peat preparatory to burning, a series of passage-ways extending upwardly from the upper portion of each peat-burning chamber circularly arranged and surrounding the retorts and annular chambers connected therewith, a cross passage-way connecting the annular chambers, a series of passage-ways or flues leading radially outwardly near the bottoms of the peat-burning or fire chambers, annular passage-ways surrounding the bottom of the chambers and gas-outlets from each annular chamber, and valves for controlling the same, and draft flues or pipes leading to beneath the grates and connecting with the central gas-flues of each retort and valves controlling the same and means whereby when the gas-outlet valve at the bottom of one chamber is open the draft-pipe at the bottom beneath the grate of the other chamber 40 is likewise opened and the other two controlling the outlet and draft pipes are closed as and for the purpose specified.
4. The combination with two peat-fire chambers and the separate gas-flues surrounding each chamber at the bottom and communicating therewith, of the outlet-pipes leading from such gas-flues, the draft-pipes leading from beneath the grates, two shafts suitably supported one above the other, a cross-arm on one shaft connected by cross connecting-bars to the cross-arm on the lower shaft and arms on each shaft located on the same

plane, cross-arms and caps connected to such arms and designed to extend over the ends of the gas-outlet pipes or flues and inlet draft-flues as and for the purpose specified.

5. The combination with two peat-fire chambers and the separate gas-flues surrounding each chamber at the bottom and communicating therewith, of the outlet-pipes leading from such gas-flues, the draft-pipes leading from beneath the grates, two shafts suitably supported one above the other, a sleeve on the upper cross-shaft, two arms connected to the sleeve and extending outwardly to one side of the upper cross-shaft, two arms secured on the shaft, the cross-arms on the bottom shaft, caps pivotally connected to one cross-arm and covering the ends of the draft-pipes and caps pivotally connected to one arm on the sleeve of the upper shaft and to an oppositely-extending arm on the shaft itself, crossed connecting-rods pivotally connected at the bottom to the ends of a cross-arm on the lower shaft and to one arm on the sleeve and one on the upper shaft, said connecting-rods being formed in two parts with lower socket portions and pins extending therethrough and the solid portion of the connecting-rods, means for manipulating such pins, so as to withdraw them and allow of the cross-arm on the lower shaft being operated independently of the arms on the upper sleeve and shaft as and for the purpose specified.

6. The combination with the outlet-flue and inner draft-flue, of the casing, a partition extending the major portion of the height of the casing into which such flue extends, a gas-conduit flue at one side of the partition, a corresponding flue on the opposite side of the partition, a pipe connecting the same, an outlet-pipe for the gas at the bottom of the outer gas-conduit flue, and inner air-flues surrounding the gas-conduit flues and forming passage-ways up around the outer gas-conduit flue and over the partition and down around the inner gas-conduit flue and communicating with the draft-tubes as and for the purpose specified.
